COSMETIC HOLDER

Rudolph N. Houlihan, Bridgeport, Conn., assignor to The Bridgeport Metal Goods Manufacturing Company, Bridgeport, Conn., a corporation of Connecticut

Application May 29, 1947, Serial No. 751,238

5 Claims. (Cl. 206—56)

1

This invention relates to cosmetic holders, particularly to the type of holder for a stick of plastic material, such, for example, as lipsticks and the like.

In a common-type of cosmetic holder, particularly a lipstick holder, the stick of plastic is mounted in a carrier which is normally enclosed in an outer body shell or casing open at one end, with means operable by relative turning movement between the enclosing shell or casing and a finger grip at the opposite end for projecting the lipstick through the open end of the casing to a position of use, and then retracting it into the casing for protection. When retracted, the open end of the shell or casing is closed by a removable cap or closure telescoped over this shell or casing. A serious objection in the common-type of holder is that, when the closure cap or cover is in place the propeller mechanism for shifting the lipstick to the position of use may be operated to advance the stick and jam it against the closed end of the cap or closure. This makes a messy condition within the holder itself, and also mars, deforms or mashes, the free end of the stick of plastic itself, and particularly is this objectionable when the device is on display in a store or on a sales counter, as it is very common for a prospective customer to pick up the holder and operate the finger grip in examining the article, with the result that the free end of the plastic stick is jammed, crushed, and forced out of shape, making the article unsalable.

It is, therefore, a principal object of the present invention to provide a simple and novel construction for this type of device, whereby when the closure cap or cover is in place over the open end of the shell or casing it is impossible to operate the propeller mechanism to feed the plastic from the enclosing shell or casing and jam it against the closed end of the cover or closure.

Another object is to provide a construction for securing the cover or closure in position on the shell or casing, in which, although the closure is retained in the closing position, it has a free turning movement with respect to the enclosing shell or casing and the finger grip or operating head, so that it is impossible while the closure is in place to cause relative movement between the shell or casing and the operating head or finger grip to propel the stick of plastic from the shell or casing and jam it against the closure.

A further object is to provide an improved and simplified means of so securing the cover or closure cap in place.

With the foregoing and other objects in view, I have devised the construction illustrated in the accompanying drawing forming a part of this specification. It is, however, to be understood that the invention is not limited to the specific details of construction and arrangement shown, but may embody various changes and modifications within the scope of the invention.

In this drawing:

10 Fig. 1 is a partial side elevation and partial section on an enlarged scale of a lipstick holder embodying my new construction.

Fig. 2 is a side elevation on a smaller scale of the inner operating sleeve;

15 Fig. 3 is a side elevation of a cooperating operating sleeve embracing the sleeve of Fig. 2;

Fig. 4 is a side elevation of the enclosing outer shell or casing;

20 Figs. 5 and 6 are side views of the free end of the outer closure cap taken at right angles to each other;

Figs. 7 and 8 are similar views of the cap showing slight modifications;

25 Fig. 9 is a top plan view of a retaining member for the closure cap or cover; and

Fig. 10 is a view similar to Fig. 1 of the lower end portion of the device and showing a somewhat modified construction.

In devices of this character the stick of plastic 11 and its operating or propeller mechanism 30 is enclosed in an outer body shell or tubular casing 12 open at both ends. Within the casing 12 is a stationary sleeve 13 provided with a spiral slot 14. This sleeve is usually rolled up from a sheet of flat metal, leaving a longitudinal slot 15, or, in other words, a split sleeve. In this type the slot 14 stops short of the opposite ends of the sleeve. In another type commonly used the spiral slot is extended through the ends of the sleeve so that a longitudinal slot 15 is not necessary. This sleeve is normally of somewhat larger diameter than the inner diameter of the shell or casing 12, so that when inserted in this shell or casing the sleeve must be compressed somewhat, then its spring or resilient action will

40 cause it to expand against the shell or casing 12 and by frictional action retain it stationary in this casing. Within the sleeve 13 is a rotary sleeve 16 provided with a straight longitudinal slot 17 provided with a short offset 18 at its outer end. This sleeve fits within the sleeve 13 and is provided with an outwardly extending annular bead 19 adjacent its upper end and an enlarged head portion 20 at its lower end, providing a shoulder 21. In assembling, the sleeve 13 is

50 placed on the sleeve 16 with the sleeve 13 com-

pressed about it, and then they are inserted in the outer casing 12 with the sleeve 13 between the shoulder 21 and the bead 19. As the sleeve 13 is frictionally held stationary in the casing 12, this will in turn by coaction with the bead 19 and the shoulder 21, retain the sleeve 16 in the casing. Also, although the sleeve 16 has frictional fit in the sleeve 13 this, however, is not sufficient to prevent turning movements of the sleeve 16 in the sleeve 13 and, therefore, with respect to the casing 12 to operate the propelling means for the carrier 22 for the lipstick or other plastic stick 11.

This carrier is preferably a cupped member slidable longitudinally in the sleeve 17, and is provided with a laterally extending lug or pin 23 projecting through the slot 17 into the spiral slot 14. It will then be seen that by rotating the sleeve 16 the slot 17 will carry the pin 23 along the slot 14, and by camming action of this pin on the inclined side walls of this slot will slide the carrier 22 and the lipstick 11 longitudinally of the casing, to either project the free end of the plastic stick for use or retract it into this casing for closure and protection. For operation of the inner sleeve 16 it is provided with an enlarged head or hand grip at its lower end. In the form of Fig. 1 it has a cupped member 24 provided with a cylindrical portion 25 telescoped and inserted in the enlarged head 20 and provided with a tight or force fit therewith so as to be in effect a part of the sleeve 16. At its closed end it is provided with an outwardly extending bead or flange 26 forming a finger grip for rotating the sleeve 16. This also forms a shoulder 27 to engage the free edge of the enlarged head 20 to limit insertion of this member into this head. It will be evident that this relative turning movement between the outer shell or casing 12 and the inner sleeve 16 operates the shifting or propeller means for the plastic stick 11. Thus, if the shell or casing 12 is held stationary and the head 26 rotated, the propeller means will be actuated, or, if the head 26 is held stationary and the casing 12 rotated, the same result will be effected. At its outer end the casing 12 is preferably extended inwardly over the ends of sleeves 13 and 16, as shown at 12a, to protect them and improve the appearance.

When not in use, the shell or casing is closed by the closure cap or cover 28 closed at its outer end 28a, and this is telescoped over the outer shell 12. In this construction, however, the inner diameter of this cap or closure is slightly greater than the outer diameter of the shell or casing 12 to provide a slight clearance 29 between them, so that the closure cap or cover 28 is sufficiently loose on the outer shell or casing to have free turning movement with respect to it, and therefore, if, when the member 28 is telescoped over the shell 12, the member 28 is held stationary or rotated while the head or grip 26 is rotated or held stationary, the shell 12 turns freely in the closing member 28, or the member 28 turns freely, and therefore there is no relative turning movement between the shell 12 and the operating head to operate the propelling mechanism for the plastic stick. Therefore, there is no danger of shifting the stick outwardly and jamming it against the closed end 28a of the enclosing cap or cover.

However, some means should be provided to retain the closure or cover 28 on the shell. In this construction, a retaining member or short sleeve 30 is telescoped over the enlargement 20 of the inner sleeve 16 with a tight or press fit, so

as to become an effective part of this enlarged head, and it is extended above the shoulder 21 and at its upper end provided with an inturned flange 31 spaced from the shoulder 21. Then at its lower end portion the closure or cover 28 is provided with one or more small outwardly extending lugs or bumps 32 which are adapted to spring by the inner edge of the flange 31, and by engaging under this flange to retain the closure member 28 in position telescoped over the outer shell or casing 12. The retaining lugs 32 have a slight clearance with respect to the flange 31 and the end of the closure with respect to the shoulder 21, so that the end of the member 28 has free turning movement within the retaining member 30, but the member 28 will yield sufficiently to permit its free end to be inserted in or removed from the retaining member 30 and permit the lugs 32 to pass by the flange 31. There may be enough spring or yield in the member 28 itself and the retaining member 30 to permit this, as with the constructions shown in Figs. 5 and 6; or if preferred, a greater movement may be provided for the retaining lugs 32 by providing one or more slits 33 on the end of the cover on either one or both sides of the lug, as shown in Figs. 7 and 8, to provide a spring ear 34 carrying the projection 32 to permit it to spring in and out as it passes the flange 31.

A somewhat modified construction is shown in Fig. 10. The operating or propeller mechanism for the plastic stick is the same as shown in Fig. 1, and the retaining means for the closure cap or cover 28 is the same as in Fig. 1, permitting free turning movement of this cap or closure with respect to the outer shell 12. However, in this construction, instead of forming a separate end member 24, telescoped into the enlarged head portion 20 of the inner sleeve 16, this head itself is formed with the outwardly extending bead or flange 26a corresponding to the flange 26 in Fig. 1 and forming a finger grip for operating the inner sleeve 16. In this case there is a shoulder 27a at the inner side of this bead corresponding to shoulder 27 of Fig. 1 to form a limit stop for positioning the cap retaining member 30. Otherwise the structure and operation is the same as that of Fig. 1.

It will be seen from the above that when the cap or closure 28 is telescoped over the outer shell or casing 12, with its inner end inserted in the retaining member 30, it is held in position by the enlarged head structure involving the portions 20, 21, member 24 and the retaining member 30, and that the connection with this enlarged head structure is a loose free turning connection, permitting free turning of the head with respect to the cap or closure 28 without operating the propeller mechanism; or it will permit free turning movement of the cap or closure 28 with respect to the enlarged head structure, which head structure also provides the finger grip for operating the propeller mechanism. Therefore, while the cap or closure 28 is in proper closing position, it is impossible to operate the propeller mechanism to project the lipstick or other plastic from its enclosing shell or casing and jam or crush it against the end 28a of the outer casing or closure.

Having thus set forth the nature of my invention, what I claim is:

1. A holder of the character described comprising a casing open at one end, a carrier for a stick of plastic or the like movable longitudinally in the casing, a head forming a rotatable finger grip at the other end of the casing, means operat-

ed by relative turning movements of the finger grip and the casing for shifting the carrier, a removable closure cap telescoped over the open end of the casing and having free turning movement relative to the casing, an inturned flange on the head of an internal diameter to receive and embrace the inner end of the cap, and outwardly extending yieldably mounted lugs on the cap adapted to spring by said flange when the cap is inserted in the flange to engage under the flange to retain the cap on the holder while permitting free turning movement of the cap.

2. A holder of the character described comprising a casing open at one end, a carrier for a stick of plastic or the like movable longitudinally in the casing, a head forming a rotatable finger grip at the other end of the casing, means operated by relative turning movements of the finger grip and the casing for shifting the carrier, a removable closure cap telescoped over the open end of the casing and having free turning movement relative to the casing, said head including an annular shoulder at the inner end of the casing, a retaining member mounted on the head and provided with an inwardly extending flange spaced above the shoulder, said flange being of an internal diameter to receive and embrace the inner end of the cap and said closure cap being provided with outwardly extending yieldably mounted lugs engaging under the flange between the flange and shoulder with a loose fit to permit free turning movement of the cap and adapted to spring by said flange for entrance and removal of the end of the cap into and from said flange.

3. A holder of the character described comprising a casing open at one end, a carrier for a stick of plastic or the like movable longitudinally in the casing, a head forming a rotatable finger grip at the other end of the casing, means operated by relative turning movements of the finger grip and the casing for shifting the carrier, a removable closure cap telescoped over the open end of the casing and having free turning movement relative to the casing, said head including an annular shoulder at the inner end of the casing and a substantially cylindrical side wall outwardly of said shoulder, a retaining member comprising a sleeve telescoped over the side wall to mount it on the head and provided with an inturned flange over and spaced from the shoulder, said flange being of an internal diameter to receive and embrace the inner end of the cap, and said closure cap being inserted in said retaining member at its inner end and provided with outwardly extending lugs between the flange and shoulder to retain the cap in position enclosing the casing while permitting free turning movement of said cap, and means yieldably mounting said lugs to spring past the flange for insertion and removal of the cap.

4. A holder of the character described comprising a casing open at one end, a carrier for a stick of plastic or the like movable longitudinally in the casing, a rotary operating sleeve in the casing, means operated by relative turning movement between the sleeve and casing for shifting the carrier, an enlarged head on the sleeve provided with an annular shoulder at the inner end of the casing, a retaining member mounted on the head provided with an inturned flange over and spaced above said shoulder, a removable closure cap telescoped over the casing and having free turning movement relative thereto, said flange being of an internal diameter to receive and embrace the inner end of the cap, the inner end of said cap being inserted in said retaining member and provided with outward projections engaged loosely between the flange and shoulder to retain the cap in position enclosing the casing while permitting free turning movements of the cap, and said projections being mounted to yield to move past the flange for insertion and removal of the cap.

5. A holder of the character described comprising a casing open at one end, a carrier for a stick of plastic or the like movable longitudinally in the casing, a rotary operating sleeve in the casing, means operated by relative turning movement between the sleeve and casing for shifting the carrier, an enlarged head on the sleeve provided with an annular shoulder at the inner end of the casing and a side wall outwardly of said shoulder, a retaining member comprising a sleeve telescoped over the side wall to mount it on the head and provided with an inturned flange over and spaced above the shoulder, a removable closure cap telescoped over the casing and having free turning movement relative thereto, said flange being of an internal diameter to receive and embrace the inner end of the cap, the inner end of the cap being inserted in said flange and provided with outward projections engaged loosely between the flange and shoulder to retain the cap in position enclosing the casing while permitting free turning movement of the cap, and said projections being adapted to yield for movement past the flange for insertion and removal of the cap.
